Primary Examiner — Susan Bennett Hattan*Assistant Examiner* — Jennifer Wright(74) *Attorney, Agent, or Firm* — Cheng-Ju Chiang(57) **CLAIM**

The ornamental design for an electronic cigarette device, as shown and described.

DESCRIPTION

FIG. 1 is a perspective view of an electronic cigarette device showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of the electronic cigarette device of FIG. 1 viewed from another viewing angle.

The diagonal shading lines shown in the drawings are intended to show transparency.

The broken lines in the drawings depict portions of the electronic cigarette device which form no part of the claimed design.
